Patented July 10, 1917.

UNITED STATES PATENT OFFICE.

HARRY L. DARAH, OF CHATHAM, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,232,507.

Specification of Letters Patent. Patented July 10, 1917.

Application filed November 21, 1916. Serial No. 132,560.

To all whom it may concern:

Be it known that I, HARRY L. DARAH, a citizen of the United States, residing at Chatham, in the county of Morris and State 5 of New Jersey, have invented certain new and useful Improvements in Telephone-Exchange Systems, of which the following is a full, clear, concise, and exact description.

This invention relates to telephone exchange systems and more particularly to 10 private branch exchange systems.

The present invention is an improvement upon the system disclosed in the Patent No. 1,175,112 to H. M. Bascom, and concerns 15 organizations of circuits and apparatus therefor for increasing the transmission efficiency of such systems and the provision of improved signaling means between the central office and private branch exchange 20 operators.

This invention is illustrated in the accompanying drawing in which a trunk circuit A extends from a central office at which is located a link circuit B, and a private branch 25 exchange at which is located a cord circuit C for interconnecting extension telephone lines D or for connecting trunk circuit A with an extension telephone line D.

Assuming that the operator at the central 30 office has been requested to make connection with an extension line which terminates at the private branch exchange, the operator will insert plug 5 of the link circuit B into the jack 6 of trunk circuit A, whereupon relay 7, located at the private branch exchange and associated with the end of the trunk circuit A terminating thereat, will be operated 35 by current from a source of supply 8. Relay 7, in operating, completes a locking circuit for itself through its right-hand winding and through its contact, whereby lamp 9 is lighted over a circuit from battery through the lower right-hand contact of key 10, winding of relay 11, lamp 9, lower 40 contact of jack 12, and contact of relay 7 to ground. The operation of relay 11 causes the operation of an alternating current 45 buzzer 13, which serves as an audible signal to the operator at the private branch exchange.

The operator at the private branch exchange, hearing the buzzer and observing the lighted condition of lamp 9, inserts front 50 plug 15 of the cord circuit C into jack 12, thereby opening the circuit of lamp 9 and

the locking circuit of relay 7, and causing the operation of relay 16 over a circuit from battery through the lower right-hand contact of key 10, resistance 17, sleeve contacts of the jack 12 and plug 15 and the winding of relay 16 to ground. The operation of relay 16 causes the operation of relay 30 which in closing its contact 29 short circuits supervisory relay 31, and in closing its upper alternate contact causes lamp 32 to be lighted. The 60 operation of relay 16 also disconnects the battery supply from, and bridges impedance coils 18 and 19 in series across, the talking strands of the cord circuit C. The impedance of these two coils is low so that tripping relay 20, associated with link circuit B, operates, whereupon relay 21 operates, locks up and permits the release of relay 22. Supervisory relay 23 is thereupon operated over a circuit from battery in the link circuit B, 70 through the upper winding of repeating coil, winding of supervisory relay 23, upper normal contact of relay 22, tip contacts of the plug 5 and jack 6, tip contacts of the jack 12 and plug 15, contact 24 of key 25, 75 impedance coil 19, contact 26 of relay 16, contact 27 of relay 28, impedance coil 18, contact 29 of relay 30, contact 35 of key 25, ring contacts of plug 15 and jack 12, ring contacts of jack 6 and plug 5, lower normal 80 contact of relay 22 and the lower winding of the repeating coil to ground. The operation of the supervisory relay 23 effaces lamp 36 which had been lighted when the plug 5 was inserted in the jack 6, the effacing of this 85 lamp indicating to the central office operator that the private branch exchange operator has answered.

The private branch exchange operator may now actuate listening-key 40 to connect 90 operator's telephone set 41 across the talking strands of cord circuit C. The actuation of key 40 closes a circuit for battery supply through relay 42 and an impedance coil 43 to the transmitter of the operator's telephone set, and in addition thereto, causes the operation of relay 33 over a circuit from battery through contact 44 of relay 16, left-hand winding of relay 33, resistance 45 and contact 46 to ground. The operation of relay 33 connects its right-hand winding in parallel with impedance coil 18, thereby serving to lock up relay 33, the source of current supply therefor being the battery across the talking strands in the link circuit 100 105 110

B. The connection of the right-hand winding of relay 33 in parallel with impedance coil 18 slightly lowers the impedance of the bridge. The operation of relay 33 also 5 opens its right-hand normal contact, thereby effacing the lamp 32, which was lighted when plug 15 was inserted in jack 12.

The private branch exchange operator being informed that connection is desired with 10 extension line D, inserts the back plug 47 in jack 48 associated with line D, whereupon lamp 49 is lighted over a circuit from battery through the upper right-hand contact of key 10, winding of relay 50, lamp 49, 15 normal contact of supervisory relay 51, sleeve contacts of plug 47 and jack 48 to ground. If the operator has restored listening-key 40 to normal position, relay 42 will be in its normal position, whereby, upon the 20 operation of relay 50, buzzer 13 operates. However, the operation of buzzer 13 at this time serves no useful purpose, so that the operator may actuate key 10 to open its left-hand contacts to stop the operation of 25 the buzzer. The operator may signal the station on line D by the operation of the usual ringing key 52.

The subscriber at the station on line D, responding to the operation of the call bell, 30 causes the operation of the supervisory relay 51, relay 51 being placed in series with the transmitter and switchhook contact of station D, which is now in parallel with the impedance bridge across the talking strands of 35 the cord circuit C. The operation of supervisory relay 51 effaces lamp 49 and causes the operation of relay 28 over a circuit from battery through contact 44 of relay 16, left-hand winding of relay 33, winding of relay 40 28, alternate contact of relay 51, and sleeve contacts of plug 47 and jack 48 to ground. Relay 28, in operating, opens its contacts 27 and 53 and closes its contact 54, thereby changing the impedance bridge across the 45 talking strands of the cord circuit from a low impedance bridge including impedance coils 18 and 19 in series with the right-hand winding of relay 33 bridged about impedance coil 18, to a high impedance bridge 50 including the impedance coil 19, right-hand winding of relay 33, impedance coil 55 and impedance coil 18 in series. This bridge is changed from low to high impedance so that if the extension subscriber should desire to 55 attract the attention of the private branch exchange operator by opening and closing the switchhook contact, this may be done without affecting the condition of the lamp 36 associated with the link circuit B.

60 At the conclusion of the conversation between extension subscriber D and the subscriber connected to the other end of link circuit B, the restoration of the receiver to the switchhook by extension subscriber D 65 causes the release of relay 51 and the light-

ing of lamp 49 to furnish a disconnect signal. Relay 28 also releases, changing the bridge across the talking strands of the cord circuit from high to low impedance. The private branch exchange operator now withdraws the plugs from the jacks, whereupon 70 supervisory relay 23 releases to light the lamp 36 to furnish a disconnect signal to the central office operator, who may now withdraw plug 5 from jack 6, thereby restoring 75 all apparatus to normal.

Suppose that, after the listening-key 40 has been restored to normal, the central office operator wishes to rering or again signal the operator at the private branch exchange. This may be done by withdrawing the plug 5 from and reinserting the plug 5 in the jack 6. Upon the withdrawal of plug 5 from jack 6, the circuit through the locking winding of relay 33 is opened, thereby 80 releasing this relay, causing lamp 32 to light. The reinsertion of the plug in the jack 6 does not reestablish the circuit through the right-hand winding of relay 33 since this 85 relay can only be energized by the actuation 90 of listening-key 40. The private branch exchange operator, noting the lighted condition of lamp 32, responds by actuating the listening-key, causing the operation and locking up of relay 33, as before described. 95

Should the subscriber on extension line D initiate a call, the removal of the receiver from the switchhook causes line lamp 60 to light and also causes the operation of relay 11, whereupon buzzer 13 operates. The operator responds by inserting plug 47 into jack 48, thereby effacing line lamp 60, and causing the operation of supervisory relay 51 to prevent the lighting of lamp 49. When plug 47 is inserted in jack 48, lamp 105 32 is lighted over a circuit from battery through lamp 32, normal contact of relay 30, normal contact of relay 31, and sleeve contacts of plug 47 and jack 48 to ground. The operator may actuate listening-key 40 and converse with the subscriber. Upon being advised that subscriber D wishes to be connected with another extension line, the operator restores listening-key 40 to normal position and inserts plug 15 into the jack 110 of another extension line. It will be noted that relay 16 does not operate, for the sleeves of the jacks associated with the extension lines are grounded while the jack associated with the trunk is connected with battery, so 115 that talking battery is supplied to the talking strands of cord circuit C through the normal contacts of relay 16. The operator may signal on the wanted extension line by operating ringing key 61. The called subscriber, responding, removes the receiver from the switchhook and causes the operation of supervisory relay 31, thereby effacing 120 lamp 32.

Should subscriber D have desired connec- 125

tion with a line terminating at the central office, the operator would have inserted plug 15 into jack 12 of the trunk A, thereby causing the operation of relay 16 to remove battery supply from cord circuit C to bridge the impedance coils 18 and 19 in series across the talking strands and to cause the operation of relay 30 to short-circuit supervisory relay 31 and place lamp 32 under control of relay 33. The establishment of the bridge across the talking strands of the cord circuit causes the operation of line relay 65 at the central office end of the trunk, thereby causing the operation of the line lamp 66. The central office operator, responding, inserts the plug 5 of the link circuit B into jack 6, thereby operating the cut-off relay associated with the trunk. The private branch exchange operator may now actuate listening-key 40 and converse with the operator at the central office. The actuation of listening-key 40 causes the operation of relay 33, as hereinbefore described.

If it is desired that extension line D be connected by means of the cord circuit C to the trunk A to be able to receive service during the night or when no operator is at the private branch exchange, this may be done by actuating key 25 and key 10 to open its right-hand contacts and by inserting plug 15 into jack 12 of the trunk circuit A and plug 47 into jack 48 of extension line 48. The actuation of key 25 by opening its normal contacts removes all apparatus from the talking strands of the cord circuit, and by closing its alternate contacts, extends the trunk line A through to extension line D. The actuation of key 10 in opening its right-hand contacts removes battery from the lamps associated with the cord circuit C and from the sleeve of the trunk circuit thereby preventing the operation of relay 16.

By employing the invention hereinbefore described, the source of ringing current is automatically disconnected from the trunk circuit immediately upon the connection of the private branch exchange cord circuit with the trunk circuit, it being very desirable that this source be disconnected before the operator's telephone set is connected with the cord circuit. This invention also provides for the reringing of the private branch exchange operator by the central office operator without the lighting of the supervisory lamp in the central office link circuit which has been a source of confusion of signals in systems heretofore employed.

What is claimed is:

1. A telephone exchange system comprising calling and called telephone lines, a link circuit for connecting the lines, a relay responsive to the connection of the link circuit with the calling line, a bridge for the talking strands of the link circuit established

upon the operation of the relay, and means for increasing the impedance of the bridge upon the removal from its switchhook of the receiver at the station on the called line connected with the other end of the link circuit. 70

2. A telephone exchange system comprising calling and called telephone lines, a link circuit for connecting the lines, a relay responsive to the connection of the link circuit with the calling line, a low impedance bridge for the talking strands of the link circuit established upon the operation of the relay, and a relay for varying the impedance of the bridge upon the removal from its switchhook of the receiver at the station on the called line connected with the other end of the link circuit. 80

3. A telephone exchange system comprising calling and called telephone lines, a link circuit for connecting the lines, a relay responsive to the connection of the link circuit with the calling line, a bridge for the talking strands of the link circuit established upon the operation of the relay, a relay for increasing the impedance of the bridge, and a circuit for the last mentioned relay controlled from the station on the called line connected with the other end of the link circuit. 85

4. A telephone exchange system comprising calling and called telephone lines, a link circuit for connecting the lines, a relay responsive to the connection of the link circuit with the calling line, a bridge for the talking strands of the link circuit established upon the operation of the relay, an operator's telephone set, means actuated to connect the telephone set to the link circuit, a relay responsive to the actuation of the means to connect a winding thereof in parallel with a portion of the bridge, and a signaling device controlled by the last mentioned relay. 90

5. A telephone exchange system comprising calling and called telephone lines, a link circuit for connecting the lines, a relay responsive to the connection of the link circuit with the calling line, a bridge for the talking strands of the link circuit established upon the operation of the relay, an operator's telephone set, a listening key for connecting the operator's telephone set to the link circuit, a relay responsive to the actuation of the listening-key to connect a winding thereof in parallel with a portion of the bridge, and a signaling device controlled by the last mentioned relay. 105

6. A telephone exchange system comprising calling and called telephone lines, a link circuit for connecting the lines, a relay responsive to the connection of the link circuit with the calling line, a low impedance bridge for the talking strands of the link circuit established upon the operation of the relay, an operator's telephone set, a 110

- listening-key for connecting the operator's telephone set to the link circuit, a relay responsive to the actuation of the listening-key to connect a winding thereof in said bridge and to lock up the last mentioned relay, a signaling device, and an operating circuit for the signaling device completed by the release of the last mentioned relay upon the opening of the calling line.
- 15 7. A telephone exchange system comprising calling and called telephone lines, a link circuit for connecting the lines, a relay responsive to the connection of the link circuit with the calling line, a low impedance bridge for the talking strands of the link

circuit established upon the operation of the relay, an operator's telephone set, a listening-key for connecting the operator's telephone set to the link circuit, a relay responsive to the actuation of the listening-key to connect a winding thereof in said bridge and to lock up the last mentioned relay, a signaling device, and an operating circuit for the signaling device controlled by the first mentioned relay and including a contact of the second mentioned relay.

In witness whereof, I hereunto subscribe my name this 20th day of November A. D., 1916.

HARRY L. DARRAH.
